SEMITRAILER SUPPORTING STRUCTURE

Filed May 3, 1940

UNITED STATES PATENT OFFICE

2,256,328

SEMITRAILER SUPPORTING STRUCTURE

Frederick M. Reid, Detroit, Mich., assignor to
 Fruehauf Trailer Company, Detroit, Mich., a
 corporation of Michigan

Application May 3, 1940, Serial No. 333,184

1 Claim. (Cl. 254—86)

This invention relates to supporting structures for semi-trailers and particularly to means for eliminating certain disadvantages thereof present in conventional constructions when employed on relatively soft surfaces.

Objects of the invention include the provision of means associated with the retractable front supporting legs of semi-trailers to prevent them from becoming imbedded to an undesired degree when contacting soft or relatively soft ground or road surfaces; the provision of means supplementary to the usual wheels or rollers at the lower ends of semi-trailer supporting legs for limiting the depth to which such rollers may be imbedded in soft supporting surfaces; the provision of a supporting leg structure for a semi-trailer having wheels or rollers at the lower ends thereof together with planular supporting surfaces arranged in co-operating but non-interfering relationship with respect to said wheels or rollers for the purpose of supplementing the bearing area of the wheels on a supporting surface upon the wheels or rollers becoming imbedded therein beyond a predetermined amount; and the provision of a retractable supporting leg structure for the front end of a semi-trailer and having rollers or wheels at the lower end thereof, together with shoes arranged in fixed relation with respect to said leg structure and provided with a planular surface adapted to be arranged in approximately parallel relation to the surface of a road when said wheels or rollers are positioned in operative relationship with respect to the same and with said planular surface spaced vertically above the lower edge of said rollers by a relatively small but material distance.

The above being among the objects of the present invention the same consists in certain novel features of construction and combinations of parts to be hereinafter described with reference to the accompanying drawing, and then claimed, having the above and other objects in view.

In the accompanying drawing which illustrates suitable embodiments of the present invention and in which like numerals refer to like parts throughout the several different views,

Fig. 1 is a side elevational view of a semi-trailer illustrating the forward end of the same as being supported in operative relationship upon the rear end of a tractor, the latter being shown in fragmentary, side elevational view, and the front supporting leg for the semi-trailer being shown in operative relation with respect to the ground;

Fig. 2 is a plan view of the semi-trailer shown in Fig. 1;

Fig. 3 is a fragmentary, front elevational view of the supporting leg structure for the semi-trailer shown in the preceding views and taken looking in the direction of the arrows 3—3 of Fig. 1; and,

Fig. 4 is a view similar to Fig. 3 but illustrating a modified form of construction.

10 Supporting leg structures for the front ends of semi-trailers are provided in a number of different types. In some constructions the legs are pivoted at their upper ends to the frame of the semi-trailer and means are provided for swinging the free ends of the legs upwardly out of contact with the ground when the front end of the semi-trailer is supported by a tractor, and downwardly into contact with the ground for supporting the front end of the semi-trailer when the tractor is withdrawn. Other constructions are provided with means for reciprocating the lower portion of the leg structure vertically to achieve the same purpose. Some of these leg structures are operated automatically by the connecting or disconnecting movement of the tractor in relation to the semi-trailer, some are operated by fluid pressure means, and some are operated manually. The present invention is adaptable for use with any of the known types of supporting leg structures but for the purpose of simplicity in description reference will be made only to that type thereof consisting of pivoted legs manually operable to operative or inoperative position, the description of the invention applied to this particular type of supporting structure making apparent to those skilled in the art how it can be similarly applied to other types of structures.

Regardless of the particular type of supporting leg structure employed for semi-trailers, such structures are universally provided with rollers at their lower ends for contact with the ground, road, or other supporting surface. Such rollers are provided primarily for the purpose of permitting ease in movement of the semi-trailer when the front end thereof is not supported by a tractor. Wheels contacting a hard surface theoretically have line contact with such surface and consequently any weight carried by the wheels exerts a high unit pressure upon the surface. Where the ground or other supporting surface is hard or relatively hard the wheels of the supporting legs of a semi-trailer are impressed into the supporting surface to such slight extent as not to materially interfere with the free rolling of the wheels upon the surface. However,

if the supporting surface is soft, and particularly where the semi-trailer is heavily loaded, the wheels at times become imbedded in the supporting surface to such an extent as not only to make it extremely difficult to move the semi-trailer without supporting the front end thereof on a tractor or the like, but oftentimes permits the front end of the semi-trailer to drop so low as to render it impossible to get the rear end of a tractor under it for the purpose of coupling the two together. This is not an uncommon occurrence where the semi-trailers are in a loading yard or the like of unpaved character and where the yard has been softened by thawing, rains, or the like.

It is the purpose of the present invention to provide means associated with such supporting legs to prevent the wheels or rollers thereof from becoming imbedded in the supporting surface therefor to an undesirable extent and to accomplish this result in a simple and economical manner.

Referring now to the accompanying drawing the numeral 10 indicates generally the frame structure of a semi-trailer and upon which a body of any suitable type or construction may be mounted in a conventional manner. The rear end of the frame 10 is supported by means of a pair of conventional wheels 12 suitably mounted upon a conventional axle structure 14 connected to the frame 10 by means of springs 16. When in operation the forward end of the frame 10 is supported upon the rear end of a tractor indicated generally at 18. For this purpose the rear end of the tractor 18 is provided with a conventional fifth wheel structure 20 and the forward end of the frame 10 is provided with a downwardly extending kingpin 22 which is received by and secured in the fifth wheel 20 for the purpose of supporting the forward end of the semi-trailer during travel and for the purpose of providing a pivotable draft connection between the tractor and trailer.

In order to provide a support for the forward end of the semi-trailer when not supported by the tractor 18, a supporting leg structure is provided adjacent the forward end of the semi-trailer which, for the purpose of illustration, is constructed as follows. At opposite sides of the frame 10 a bracket 24 is fixed to the outer lower faces of the opposite frame side members. Pivotally secured to each of the brackets 24 as by means of a pin 26 is a supporting leg 28. This supporting leg may, if desired, be made in two or more longitudinally adjustable sections securable together in longitudinally adjustable position for permitting the effective rigid length of the legs 28 to be adjusted in service if desired. However, it will be understood that once the legs 28 are adjusted for length they are locked in such position and usually remain in such position during their life. The lower ends of the legs 28 are bifurcated as indicated in Fig. 3.

Extending between and fixed to the lower ends of the legs 28 is a shaft or axle 30. The ends of the axle 30 project through the bifurcated lower ends of the corresponding legs 28, and each rotatably receives thereon within the bifurcation a supporting wheel or roller 32. Cross-braces such as 34 are preferably provided between the legs 28 for the purpose of bracing them transversely of the semi-trailer.

In order to move the legs 28 and rollers 32 from a position in which the legs and rollers support the forward end of the semi-trailer from

the ground to a position in which the wheels 32 are drawn upwardly out of possible contact with the ground for travelling purposes, and to provide suitable braces for the legs when in operative position, the following mechanism is provided. A rigid strut 36 is pivotally secured at one end thereof to each leg 28 immediately above the shaft or axle 30. The struts 36, as shown, extend rearwardly and upwardly and at the same time inwardly so as to bring their upper ends together or substantially together adjacent the longitudinal center line of the semi-trailer immediately below the frame 10. At the latter location the upper and rearward ends of the struts 36 are pivotally connected to a block member 38 supported for longitudinal sliding movement on a slide structure 40 fixed to the frame 10 centrally thereof and extending longitudinally thereof between a suitable pair of cross-members of the frame 10.

The block 38 is provided with an upwardly extending nut portion 42 within which is threadably received a longitudinally extending screw 44 suitably supported by the frame for rotatable movement but fixed against relative axial movement. As best illustrated in Fig. 2 the forward end of the screw 44 extends into and is carried by a gear box 46 and within the gear box 46 has fixed thereto a bevel gear 48 which lies in mesh with another bevel gear 50 secured to a shaft 52 which extends out through the gear box 46 and through the side of the frame 10 where its outer end is supported in a bracket 54 fixed to the frame. A crank 56 is provided on the outer end of the shaft 52.

It will be appreciated that by turning the crank 56, the shaft 52 and gear 50 will be rotated, thereby causing rotation of the gear 48 and screw 44. Rotation of the screw 44 will cause the nut 42 and consequently the block 38 to move longitudinally of the slide or guide 40 depending upon the direction of rotation of the crank 56, and movement of the block 38 longitudinally of the vehicle will cause a corresponding longitudinal movement of the upper end of the struts 36 and consequent pivotal movement of the legs 28 about the pivot pins 26 to raise or lower the wheels 32. It will be understood that when the front end of the semi-trailer is not supported by a tractor, such as 18, the legs 28 are moved to their operative position illustrated in Figs. 1 and 2 with the wheels 32 in contact with the ground, and that after a tractor such as 18 has backed under the front end of the semi-trailer and has been locked thereto, the crank 56 will be operated to move the block 38 rearwardly and swing the legs 28 in a counterclockwise direction of rotation as viewed in Fig. 1 about the pivot pins 26 so as to raise the wheels 32 upwardly out of contact with the ground, such wheels being returned into contacting relationship with the ground prior to uncoupling of the tractor from the front end of the semi-trailer.

In accordance with the present invention in order to prevent the wheels 32 from being buried in the supporting surface when the supporting surface is unduly soft and/or when the semi-trailer is heavily loaded, I provide supplementary bearing surfaces in association with each of the wheels 32 and symmetrically arranged with respect thereto, which bearing surfaces become operative only after the wheels 32 have become imbedded a predetermined amount in such road or other supporting surface.

In the particular construction illustrated in

Figs. 1, 2 and 3 such supplementary bearing surfaces take the form of a shoe 60 formed integrally with the lower end of each side of the bifurcated lower end of each leg 28 and each shoe has a relatively flat bottom surface arranged to lie in substantially parallel relation with respect to the surface of the ground when the legs 28 are in their down or operative position. The ends of the shoes are preferably upwardly turned or curved as best illustrated in Fig. 1. Each shoe 60 is preferably arranged in relatively close proximity with its corresponding wheel 32 but sufficiently spaced therefrom as to be out of interfering relation with respect thereto. Its lower face is preferably positioned in a plane sufficiently vertically spaced above the lower face of the corresponding wheel 32 that it will come into contact with the supporting road or other surface only after the corresponding wheel 32 has begun to embed itself into such surface to an undesirable extent. Preferably the lower face of the shoes 60 are spaced an inch to an inch and a half above the lower face of the wheel 32, but it will be appreciated that this dimension may be varied one way or another depending upon conditions or the desires of the individual designer.

In any event the lower face of each shoe 60 is of a material area as compared to the projected area of the peripheral surface of the corresponding wheel 32 so that when the corresponding wheel 32 embeds itself into a supporting surface, a sufficient amount to bring the shoes 60 into contact with such surface, the area of contact between the supporting leg structure and the supporting surface is increased to an extent ordinarily sufficient to prevent any further material embedding of the supporting leg structure in the supporting surface. The shoes 60 being upwardly spaced with respect to the lower surface of the cooperating wheel 32, when the supporting surface is in firm or in hard condition the shoes 60 will not come in contact therewith and no interference with the normal action of the wheels 32 will result. It will thus be appreciated that the shoes 60 are auxiliary to the wheels 32 and come into action only under those conditions where the supporting surface is in such condition as to warrant an additional bearing area between the supporting leg structure and such surface.

In some constructions the lower ends of the supporting legs are not bifurcated and one wheel 32 is provided on the shaft or axle 30 on each

side of each supporting leg in order to increase the available bearing area between the supporting leg structure and the ground. Such construction is illustrated in Fig. 4. Where such construction is employed, the leg 28 previously described may be modified to provide a shoe structure by extending the leg 28''' downwardly below the shaft or axle 30 and forming on the lower end thereof a shoe 60''', corresponding in position, function and results to the shoes 60 previously described. The shoe 60''' in this case is, of course, located midway between the wheels 32 as illustrated in Fig. 4, and, therefore, symmetrical with respect thereto.

From the above description it will be appreciated that the present invention provides a simple and effective means for limiting the amount which the usual wheels or rollers of the supporting leg structure of a semi-trailer may embed themselves in a supporting surface where the supporting surface is relatively soft, the load on the trailer is relatively large, or both these factors occur simultaneously, and that by limiting the embedding of the wheels in the supporting surface a real and material advantage is gained.

Formal changes may be made in the specific embodiments of the invention described without departing from the spirit or substance of the broad invention, the scope of which is commensurate with the appended claim.

What I claim is:

In a semi-trailer, in combination, a pair of retractable leg members, a shaft interconnecting corresponding ends of said members, a wheel structure carried by said shaft adjacent each of said members, each of said members having rigidly fixed thereto downward extensions having relatively flat shoe means of material area arranged in a plane approximately normal to the length of said members, each said flat shoe means being symmetrically positioned with respect to the associated wheel structure, and being positioned intermediate said shaft and the peripheries of the wheels whereby to provide an auxiliary ground engaging surface adapted to support the semi-trailer at a fixed height in the event that the wheels sink into a soft supporting surface, means for raising and lowering that end of said members carrying said wheels, and means for operatively connecting the opposite ends of said members to said trailer.

FREDERICK M. REID.
